J. G. Shands,

Dressing Millstones.

No 10,674.

Patented Mar 21, 1854.

Fig 2.

UNITED STATES PATENT OFFICE.

J. G. SHANDS, OF ST. LOUIS, MISSOURI.

MACHINE FOR DRESSING MILLSTONES.

Specification of Letters Patent No. 10,674, dated March 21, 1854.

To all whom it may concern:

Be it known that I, J. G. SHANDS, of the city of St. Louis and State of Missouri, have invented a new and useful Implement for Dressing Millstones; and I do hereby declare that the following is a full, clear, and exact description of the construction and operation of the same, reference being had to the accompanying drawings, making a part 10 of this specification, in which—

Figure 1 is a side view of my implement. Fig. 2 is a plan or top view of the same, showing the manner in which the implement is applied to a mill stone.

15 Similar letters of reference indicate corresponding parts in the several figures.

This invention relates to a new and useful implement for picking and dressing mill stones, and consists in placing the wiper wheel, which operates the pick spindle or arbor within a swinging frame, by which a greater or less vibration may be given the arbor, and the pick be made to descend upon the stone with the requisite degree of force.

20 25 To enable others skilled in the art to make and use my invention, I will proceed to describe its construction and operation.

A represents a rectangular frame, on the upper part of which a carriage P is placed, 30 said carriage fitting on a way (a,) on one side of the frame.

C is a stock the base of which fits in the carriage B in dovetail form as shown in Fig. 1, a groove or recess (b,) see Fig. 2, 35 being in the upper surface of the carriage in which the stock C slides in a direction transversely with the frame A. On the front of the stock C, is the pick arbor D, which works in suitable boxes (c) (c'). On 40 the arbor D, there is a fixed circular ledge or collar (d) between which and the upper box (c') there is a spiral spring (e), said spring encompassing the arbor. See Fig. 1.

Around the arbor D, and above the upper 45 box (c') there is another spiral spring (f), see Fig. 1, the upper part of which bears against a nut (g) on the upper part of the arbor on which for a short distance a screw thread is cut.

50 D', is the pick secured to the lower end of the arbor. See dotted lines, Fig. 1.

E, is a swinging frame of V shape having a hub or boss (h) at each side through which a shaft F runs, said shaft fitting in 55 bearings (i) (i) at the ends of arms (j) (j)

which project outward at each side of the stock C, as shown in Fig. 2.

G, is a shaft at the front of the swinging frame having upon it the wiper wheel H and two toothed wheels I, I, one on each 60 side of the wiper wheel. These wheels I, I, gear into two toothed wheels J, J, on the shaft F.

L, is a crank at one end of the shaft F.

M, see dotted lines, Fig. 1, is a shaft 65 placed in the carriage B, and having a pinion (k) on its inner end which gears into a rack (l) on the under side of the base of the stock. On the outer end of the shaft M there is a ratchet wheel N, into which a 70 pawl (m) catches, said pawl being attached by a pivot (n) to an upright lever O.

P, is a ring or collar attached by a pivot (p) to the front part of the frame A.

R, is a pawl at the back of the swinging 75 frame, said pawl catching into the teeth of a rack S, on the back of the stock C.

Operation: The implement is placed upon the stone T, to be picked or dressed, and the ring or collar is placed over the spindle U, 80 at the center of the stone, so that the frame A will be in line or parallel with a section of furrows (r), see Fig. 2, in which the spindle, section of a stone, and furrows are shown in red. The crank L, is then turned, 85 and the wiper wheel H, as it rotates strikes the fixed ledge or collar (d) on the arbor D, and raises the arbor, which, when the ledge or collar is freed from the wiper wheel, is forced down by the spiral spring (e). The 90 length of the vibrations of the arbor D, may be made greater or less by adjusting the frame E. For instance, if the front end of the frame is depressed the wiper wheel will not act so much upon the ledge or collar (d) as when the frame is in a horizontal 95 position. The greater the length of the vibration the more the spring (e) will be compressed when the arbor is raised and consequently the arbor will descend with proportionally greater force, the pick D', acting 100 upon the stone T. The swinging frame is retained in the desired position by the pawl R and the rack S. To pick or sharpen the furrows (r) the carriage B is gradually 105 moved back and forth upon the frame A,

the pick being directly over the furrows operated upon, the pick traversing the width of the furrow by sliding the stock C in the groove (b) in the carriage by means of the 110

lever O, ratchet N, shaft M, and pinion k, which gears into the rack (l) on the under side of the base of the stock, the lever O being operated by the finger.

5 In dressing mill stones the force of the blow of the pick requires to be graduated very nicely. If this is not attended to, soft places in the stone will be scored or hollowed out, leaving an uneven surface. By adjusting or screwing down the nut (g,) on the upper part of the arbor D, the force of the spring (e) underneath the box (c') will be counteracted in a measure, by the spring (f,) on the arbor above the box (c'). The 5 whole surface of the stone may be dressed by turning the frame around on the stone, the collar or ring P being upon the spindle U.

0 By the within described implement mill stones may be dressed or picked in a perfect

manner and in a much shorter time than they can be dressed or picked by hand. It is a labor saving machine, and by its use an experienced or skilful hand is not necessarily required to put a pair of mill stones 25 in perfect order.

Having thus described my invention, what I claim as new and desire to secure by Letters Patent, is,

Placing the wiper wheel H, which operates the arbor D, and pick D', on a swinging frame E, as herein shown and described by which a greater or less length of vibration may be given the arbor D, and the pick be made to act with a corresponding degree 30 35 of force upon the stone.

J. G. SHANDS.
